UNITED STATES PATENT OFFICE

2,071,508

HOUSE CAR

Frank Ditchfield, Cleveland, Ohio, assignor to The
Youngstown Steel Door Company, Cleveland,
Ohio, a corporation of Ohio

Application October 25, 1933, Serial No. 695,066

9 Claims. (Cl. 105—409)

This invention relates to improvements in house cars.

A great many box cars of the type commonly known as single sheathed house cars are now in use on the railroads, these cars comprising a steel underframe including channel side sills; steel side plates, usually angles or Z bars; pressed steel side posts and diagonal braces riveted at their ends to the side plates and side sills; sheet metal ends; and wood side wall sheathing applied to the inner sides of the posts and braces, one exemplification of such a house car being known as U. S. R. A. standard steel underframe single sheathed box car. As well known to those skilled in the art, the wood sheathing of such single sheathed house cars, after being in service for any considerable time, permits leakage due to shrinkage of the boards, the driving of nails therethrough for the purpose of fastening the lading, and other abuses, particularly at the rear of the door where pinch bars are frequently used in forcing the doors to closed position. As is also well known, there is a constantly growing demand for all steel cars because of their greater durability, strength, lesser maintenance costs and freedom from leakage.

At the present time, therefore, railroad officials are confronted with the problem of determining whether or not to try and keep in repair the present single wood sheathed cars now on hand by renewing the wood sheathing, with the attendant expense and recurring repair bills sure to follow, or to meet the demand for an all metal car with steel sheathing having greater strength, durability, freedom from leakage and lesser maintenance costs. In the great majority of said single wood sheathed cars, the steel underframes, posts, braces, metal ends and side plates are still serviceable and reusable. To replace the entire superstructure of such wood sheathed box cars would entail relatively great expense and it is obvious, therefore, that it is to the great advantage of the railroads in meeting the demands for an all steel car, to reuse or salvage all of the steel parts of the superstructure in a converted arrangement to thereby minimize the expense of conversion from wood to all steel while at the same time providing a far more satisfactory car.

One object of this invention is to provide an all steel or metal sheathed box car or other type of house car, of simple, efficient and durable construction and more particularly such a car that may readily be converted from a wood single sheathed box car wherein all of the original

metal underframe, metal ends, side plates, side posts and braces may be retained in their original positions and condition and combined with the metal sheathing to thereby minimize the cost of conversion.

Another object of the invention is to provide a metal sheathed box car of the type indicated in the preceding paragraph, wherein special provision is made to eliminate or minimize possibility of the sheathing being perforated or otherwise injured by reason of nails driven from the inside of the car in securing the lading.

A specific object of the invention is to provide metal side wall sheathing for a car converted from a standard single wood sheathed car such that the metal sheathing may be applied in place without disturbing any of the original attachments of the posts and braces to the side plates and side sills to the end that the labor expense in converting the car is kept down to a minimum.

Other objects of the invention will more clearly appear from the description and claims herein-after following.

In the drawings forming a part of this application, Figure 1 is a side elevational view of a car embodying the improvements, the portion of the car shown being from the usual side door opening to one end, parts being broken out to better accommodate the view on the sheet. Figures 2 and 2^a, combined, constitute a horizontal section of the car from car end to door post, corresponding to the section line 2—2 of Figure 1 but upon a somewhat enlarged scale. Figure 3 is an enlarged, horizontal sectional view of the corner portion of the car to more clearly illustrate certain details of construction. Figure 4 is an enlarged, horizontal detailed sectional view corresponding to the line 4—4 of Figure 1. And Figure 5 is a vertical, sectional view through the car side corresponding substantially to the line 5—5 of Figure 2.

While Figure 1 illustrates only approximately one half of one side of the car, it will be understood that the other half of the side of the car will be complementary thereto and that the two sides of the car will be similar.

In said drawings, A indicates one of the channel side sills of the car; B one of the cross members of the steel underframe; C one of the side plates, the same being of special angle section as commonly found in standard single sheathed box cars; D—D pressed intermediate steel side posts; E—E pressed steel diagonal side braces; F a Z bar door post; and G a metal end. The parts hereinabove specifically referenced correspond to

those now found in standard single wood sheathed box cars and, in carrying out the present invention with reference to such a car converted to an all steel car, are left intact. As will be understood by those skilled in the art, where the present invention is embodied in a converted car, minor variations as to certain of the parts will be found in single wood sheathed box cars but essentially the one chosen for illustration is fairly representative of its class. As will be also understood, the present invention may obviously be carried out in connection with completely new cars, although especially adapted for conversion of old single wood sheathed cars.

15 In carrying out the present invention, each half of a car side is comprised of a plurality of sheet metal panels K and L, there being one of the former between each corner of the car and nearest side post D and generally three of the 20 panels L between said side post and the door post. Each of said panels is of rectangular outline and of a width corresponding to the distance between adjacent pairs of posts or post and corner of the car as the case may be and of a height to underlap the side plate and so as to extend down to a line slightly above the side sill, as shown in Figure 5. The end panels K differ somewhat, however, from the other panels L by reason of the absence of any diagonal brace at the end of the 25 car and also to allow for attachment of the usual grab iron and ladder rungs.

Referring first to the panel K, the same is shown as provided with a vertically extending wide flat margin 10, the edge of which is underlapped and riveted to the side flange 11 of the metal end G as by the vertical series of rivets 12. The width of said flat portion 10 will be made such as to allow for the attachment of the grab irons, one of which is indicated at 13 and the 40 ladder rungs 14 on the opposite side of the car, said ladder rungs being indicated by dotted lines in Figure 1. Between the flat marginal portion 10 and the adjacent side post D, the panel K is formed with an outwardly extended rectangular 45 dished portion 15 of a height and width corresponding to the space defined by the side plate, post, flat marginal portion 10 and a line slightly above the top of the side sill. Said outwardly dished portion 15 is of a depth corresponding to 50 the depth of the side post and is united to the flat portions of the sheet in the original plane of the latter around all sides by outwardly inclined vertical and horizontal sections 16-18 and 55 19-21.

Each of the panels L is of generally similar formation except that, instead of a rectangular outward dished formation, it is provided with two complementary outwardly dished triangular formations 18 and 19, each corresponding to the triangular space defined, one by a side post, side plate and diagonal brace and the other by a diagonal brace, side post and side sill. Where each panel L passes under a diagonal brace E, 60 the sheet is provided with a flat portion 20 in the original plane of the sheet and which extends diagonally in alignment with the brace. As in the case of the panel K, each of the dished formations 18 and 19 is united with the flat portions 65 of the sheet in the original plane thereof by outwardly inclined sections 21, 22 and 23 paralleling, a side post, side plate and brace respectively and similar sections 24, 25 and 26 paralleling a diagonal brace, side post and side sill, respectively.

70 All panels along their top edges are lapped

under the depending flange 27 of the angle side plate C and secured thereto by the horizontal series of rivets 28. The vertical flat edges of the panels are similarly underlapped and riveted to the respective side flanges 29-29 of the posts as 75 by the vertical series of rivets 30-30. At the door post, the adjacent panel is similarly lapped under the inner flange 31 of the Z bar door post F and secured thereto by the vertical series of rivets 32. Where each of the panels L underlies 10 a diagonal brace E, it is riveted to the inner face of the latter as by the rivets 33 extended through the flanges of the pressed brace, each of the latter and the side posts being of substantially U or bath tub section, as shown.

To provide a rigid and weatherproof union between the side sheathing and the side sill, a floor angle 34 is employed, the same extending from door post to end wall of the car, said angle 20 having its outer upper extended flange underlapping and secured to the bottom marginal edge of the sheathing by the horizontal series of rivets 35. The lower inwardly extended leg 36 of the angle overlies and is riveted to the inturned top flange of the side sill A as by the series of rivets 37. In addition to the angle 34 serving to rigidify the lower edge of the sheathing and form a weather tight union with the side sill and support for the floor boards 38 laid thereon and secured by rivets 39, said angle performs another important function due to the fact that its outer vertical flange is extended above the floor boards and thus serves as a fender to prevent moisture from the interior of the car reaching the panel sheets at the side sill level. This is of importance, inasmuch as it eliminates any question of the thickness or gauge of the sheets to resist corrosion and permits of the same being made of lighter gauge than would otherwise be possible. Said upstanding flange also eliminates danger of any nails being driven through the sheathing at the floor line, as will be apparent from inspection of Figure 5.

The roof of the car may be of any desired construction, the same being shown as comprised of roof sheets 40, carlines 41 with an interposed angle 42 to which the downturned edges of the roof sheets are riveted, said angle being in turn riveted to the top outwardly sloping flange 43 of the side plate.

Where the panel sheets are extended under the side plate adjacent the posts, as best shown in Figure 5, the slight openings or gaps that would otherwise be present are closed, preferably by welding, as indicated at 44.

To provide for attachment of the usual inner wood lining for the car, each of the posts D has secured within the channel formation thereof vertically extending wood nailing strips 45, the latter being secured to the posts by rivet bolts 46 as best shown in Figure 4. Intermediate each pair of posts D, wood spacers or fillers 48-48 are employed. The latter are secured in place to the outwardly dished portions of the panels by angle clips 47, it being understood that said fillers 48 are chamfered off at their upper and lower ends to correspond with the inclined sections 22 and 26 of the panels and are also of reduced thickness, as indicated at 48, where the same 70 pass the flat sections 20 of the panels in line with the braces. A corresponding filler 48 is employed in the center of the panel K and secured to the latter likewise by angle clips 47.

The nailing strips 45 and fillers 48 and 49 are 75

so proportioned as to have their inner surfaces in a plane corresponding to the inside plane of the original wood sheathing so that, when the inner wood lining 50 is applied in place, there 5 is a space left between the outer surface thereof and the adjacent flat portions of the panels in the original plane of the latter to an amount corresponding to the thickness of the original wood sheathing, less the thickness of the metal 10 sheathing, one of such spacings being indicated at 51 in Figure 4. With this arrangement, there is only slight possibility of any lading attaching nails driven through the lining adjacent the posts penetrating through to the metal sheathing but should any such nails be long enough 15 to encounter the lapped edges of the sheathing, the same will be prevented from injuring or passing therethrough due to the outer reinforcement or backing of the post flanges. Similarly, any 20 nails that may be driven through the lining adjacent the edges of the braces will be prevented from perforating the metal sheathing. The main outwardly dished portions of the sheet metal panels are obviously spaced sufficiently outwardly 25 from the lining as to eliminate danger of being perforated by nails driven through the lining and should any nails be driven outwardly through the lining slightly outside of the flanges of the posts or braces, the ends of such nails 30 would encounter the sloping or inclined sections 18, 21, 23, 24 and 25 and be deflected thereby so as to avoid perforation and injury to the sheathing and thus preserving the leak-proof character 35 of the latter. To prevent danger of the flat marginal portion 10 of the end panel K from being perforated by any nails, the same is reinforced by a rectangular panel 52 secured to the inside thereof, extending from the bottom of the panel upwardly to such point as is above any line 40 below which nails are ordinarily driven through the lining for securing the lading.

From the preceding description, it will be seen that, in the case of a converted single wood sheathed car, after the original wood lining is 45 torn out, each of the panels K and L may be readily inserted in place from the inside of the car and riveted to the respective frame members without disturbing the position or condition of the latter. The bottom angle 34 obviously may 50 be applied after all the panels are in place, thus completing the steel side wall. As will be further evident, the metal sheathing provided is such as to involve a minimum outlay for material and minimum outlay for application to the 55 superstructure framework. The dished or other integral rigidifying formation of the panels obviously adds to their strength as well as forming a safeguard against perforations from nails and the completed wall functions as a true girder 60 with the top cord provided by the side plate and the bottom cord by the side sill and bottom angle 34 and the struts and braces by the posts D and braces E all rigidly riveted to the side plate and side sill, as shown.

65 Although the invention has been described with particular reference to the conversion of a single wood sheathed car, it is obvious that the construction disclosed may be incorporated in new cars. While the preferred embodiment of the invention 70 has herein been shown and described, the same is merely illustrative and all changes and modifications are contemplated that come within the scope of the claims appended hereto.

What is claimed is:

75 1. A house car comprising: metal side sills;

metal side plates having depending flanges; sheet metal ends; and a side wall structure with a door opening on each side of the car; each said side wall structure comprising metal door posts, metal intermediate posts, metal diagonal braces between each pair of intermediate posts and intermediate posts and door posts, all of said posts and braces being secured at their ends directly to the outer faces of the respective side plate depending flanges and to the side sill, and a plurality of rectangular 10 sheet metal panels, the corner end panels each extending between and secured along its vertical edges to the corresponding car end and adjacent side post and provided with an outwardly offset, rectangular, dished formation spaced from the 15 corner a distance corresponding approximately to the ladder spacing, each of the remaining panels being of a width corresponding to the space between two adjacent posts and each having two oppositely arranged and outwardly disposed triangular dish formations disposed in the spaces defined by the posts, braces, side plate and side sill; reinforcing plates on those portions of said corner end panels which correspond to said ladder spacing; reinforcing plates for said corner 20 end panels extending continuously from each car end to said dished formation of said end panels; and a floor angle riveted to the bottom edges of the 25 panels and to the top of the side sill.

2. A house car including: a metal side sill; 30 a metal side plate having a depending flange; metal side posts; metal diagonal braces, the braces and posts being secured at their top and bottom ends directly to the outer face of said side plate flange and to the side sill respectively, said posts and braces each having flanges extending lengthwise thereof; sheet metal side wall sheathing secured to the inner faces of said flanges of the posts and braces, said metal sheathing in the spaces defined by the posts, braces, side plate and side sill being outwardly offset, said offset portions 35 being united to those portions of the sheathing secured to the inner faces of said post and brace flanges by continuous, outwardly inclined sections paralleling and disposed immediately adjacent 40 said flanges of the posts, braces and side plate, a wooden lining extending between said posts, means for fastening said lining in position in abutting relationship with said posts, whereby perforation of the sheathing from nails driven from 45 the inside of the lining is minimized.

3. A single metal sheathed house car converted from a single wood sheathed house car, said wood sheathed car having the wooden sheathing of the side walls removed, the side posts and diagonal braces, side plates and side sills of said car remaining in their original position, an angular member secured to each side sill having a flange extending vertically and metallic sheathing secured to the remainder of each of said side 55 walls, said sheathing being placed from the inside, flange extending vertically and metallic sheathing being overlapped upon said vertical flange of said angular member and the upper margin of said sheathing being disposed so as to be overlapped by the corresponding side plate, and means 60 securing the sheathing of each side wall to said posts, braces, side plate and vertical flange of said angular member.

4. A single metal sheathed house car converted from a wood sheathed house car, said latter car having side walls each comprising a side plate having a vertical flange, a side sill, side and door posts and diagonal braces secured to said side plate and sill and wooden sheathing and metal- 65

lic ends, said sheathing being removed while maintaining said side plate, side sill and posts and braces in their original position and in their original condition, a metallic angular member secured to said side sill having a vertical flange extending substantially between each door post and the corresponding end of the car, a plurality of metallic end and intermediate panels associated with said side plate, posts, braces, angular members and car ends and providing the sheathing for said side wall, each of said intermediate panels being positioned from the inside of the car with its lower margin in overlapping engagement with the vertical flange of said angular member, its upper margin in underlapping engagement with the vertical flange of said side plate and its vertical margins underlapping corresponding posts, means securing said margins to said parts with which they have lapping engagement and means securing each panel to a corresponding side brace.

5. A single metal sheathed house car converted from a wood sheathed house car, said latter car having side walls each comprising a side plate having a vertical flange, a side sill, side and door posts and diagonal braces secured to said side plate and sill and wooden sheathing and metallic ends, said sheathing being removed while maintaining said side plate, side sill and posts and braces in their original position and in their original condition, 10 a metallic angular member secured to said side sill having a vertical flange extending substantially between each door post and the corresponding end of the car, a plurality of metallic end and intermediate panels associated with said side plate, posts, braces, angular members and car ends and providing the sheathing for said side wall, each of said intermediate panels being positioned from the inside of the car with its lower margin in overlapping engagement with the vertical flange of said angular member, its upper margin in underlapping engagement with the vertical flange of said side plate and its vertical margins underlapping corresponding posts, each of said intermediate panels being provided with outwardly dished triangular portions separated by plane diagonal portions disposed within the triangular areas defined by the posts, braces, side plate and side sill, said triangular panel portions being connected with said marginal panel portions and plane diagonal portions by outwardly inclined portions extending continuously from the adjacent edges of said posts, braces and vertical flanges of said side plate and angular member; means securing said intermediate panels to said posts, braces and vertical flanges of said side plate and angular member and a wooden lining for each side wall secured to said posts in spaced relationship to said outwardly dished panel portions for the purpose set forth.

6. A single metal sheathed house car converted from a wood sheathed house car, said latter car having side walls each comprising a side plate having a vertical flange, a side sill, side and door posts and diagonal braces secured to said side plate and sill and wooden sheathing and metallic ends, said sheathing being removed while maintaining said side plate, side sill and posts and braces in their original position and in their original condition, a metallic angular member secured to said side sill having a vertical flange extending substantially between each door post and the corresponding end of the car, a plurality of metallic end and intermediate panels associated with said side plate, posts, braces, angular members and car ends and providing the sheathing for said

side wall, each of said intermediate panels being positioned from the inside of the car with its lower margin in overlapping engagement with the vertical flange of said angular member, its upper margin in underlapping engagement with the vertical flange of said side plate and its vertical margins underlapping corresponding posts, each of said intermediate panels being provided with outwardly dished triangular portions separated by plane diagonal portions disposed within the triangular areas defined by the posts, braces, side plate and side sill, each of said end panels being provided with an outwardly dished substantially rectangular portion and a flat portion lying in the main plane of said panels, said triangular dished panel portions and said marginal portions, and said rectangular dished portions and a vertical marginal portion, upper and lower marginal portions and the plane portion of said end panels being connected by outwardly inclined portions extending continuously from the corresponding adjacent edges of said posts, braces, vertical flanges and said side plate and angular member and said plane portions of said end panels to said dished portions of said panels, said plane portions of said end panels being secured to said car ends and being reinforced by metallic plates extending continuously from said ends to the adjacent outwardly inclined portion of each end panel; means securing said panels to said posts, braces and vertical flanges of said side plate and angular member and a wooden lining for each side wall, said lining being secured to said posts in spaced relationship to said outwardly dished portions of said panels for the purpose set forth.

7. The art of converting single wood sheathed house cars having metallic side plates having vertical depending flanges, metallic side sills, metallic side and door posts and diagonal braces secured to said side plate and side sill and defining triangular areas therewith, metallic ends and wooden sheathing to single metal sheathed house cars comprising removing the wooden sheathing while leaving the metallic portions of said car in the same position and condition, securing metallic members to said side sills, said members extending from each car end to the adjacent door post, applying metallic intermediate panels having outwardly dished triangular portions connected with plane, marginal and diagonal portions by outwardly inclined portions extending continuously between said plane and dished portions to a side wall of the car from the inside thereof, disposing the lower margins of said intermediate panels in overlapping engagement with said metallic members, swinging the upper margins of said panels into underlapping engagement with said side plate flange so as to dispose the dished triangular portions thereof in the said triangular areas and said plane, marginal and diagonal portions in underlapping engagement with said posts and diagonal braces, said plane portions of said panels terminating at the edges of the members defining the triangular areas, applying metallic end panels to said side walls from the inside thereof, overlapping the lower margins of said end panels upon said metallic members, swinging said panels into underlapping engagement with said side plate flange and adjacent post and fastening all said panels to the members with which they are lapped and to the car ends.

8. The art of converting single wood sheathed house cars having metallic side plates having

vertical depending flanges, metallic side sills, metallic side and door posts and diagonal braces secured to said side plate and side sill and defining triangular areas therewith, metallic ends and wooden sheathing to single metal sheathed house cars comprising removing the wooden sheathing while leaving the metallic portions of said car in the same position and condition, securing metallic members to said side sills, said members extending from each car end to the adjacent door post, applying metallic intermediate panels having outwardly dished triangular portions connected with plane, marginal and diagonal portions by outwardly inclined portions extending continuously between said plane and dished portions to a side wall of the car from the inside thereof, disposing the lower margins of said intermediate panels in overlapping engagement with said metallic members, swinging the upper margins of said panels into underlapping engagement with said side plate flange so as to dispose the dished triangular portions thereof in the said triangular areas and said plane, marginal and diagonal portions in underlapping engagement with said posts and diagonal braces, said plane portions of said panels terminating at the edges of the members defining the triangular areas, applying end panels having outwardly dished substantially rectangular portions terminating short of one vertical end of said panels and connected with plane marginal portions thereof by outwardly inclined portions extending continuously between said plane and dished portions from the inside of the car, overlapping

the lower margins of said end panels upon said metallic members, swinging said end panels into underlapping engagement with said side plate flange and adjacent post so that the plane marginal portions engaging said post, side plate flange and metallic member terminate at the contiguous edges thereof, reinforcing the remaining plane marginal portions of said end panels, securing said panels to the members with which they are lapped and to the car ends and securing a wooden lining to said posts in spaced relationship to said outwardly dished portions of said panels.

9. A house car including: a metallic side sill; a metallic side plate having a depending flange; 15 metallic side posts; said posts being secured at their top and bottom ends to the outer face of said side plate flange and to the side sill respectively, said posts each having flanges extending lengthwise thereof; sheet metal side wall sheathing secured to the inner faces of said flanges of the posts, said metallic sheathing in the spaces defined by the posts, side plate and side sill being outwardly offset, said offset portions being united to those portions of the sheathing secured 25 to the inner faces of said post flanges by continuous outwardly inclined sections paralleling and disposed immediately adjacent said flanges of the posts and side plate, a wooden lining extending between said posts, means for fastening 30 said lining in position against said posts whereby perforation of the sheathing from nails driven from the inside of the lining is minimized.

vertical depending flanges, metallic side sills, metallic side and door posts and diagonal braces secured to said side plate and side sill and defining triangular areas therewith, metallic ends and wooden sheathing to single metal sheathed house cars comprising removing the wooden sheathing while leaving the metallic portions of said car in the same position and condition, securing metallic members to said side sills, said members extending from each car end to the adjacent door post, applying metallic intermediate panels having outwardly dished triangular portions connected with plane, marginal and diagonal portions by outwardly inclined portions extending continuously between said plane and dished portions to a side wall of the car from the inside thereof, disposing the lower margins of said intermediate panels in overlapping engagement with said metallic members, swinging the upper margins of said panels into underlapping engagement with said side plate flange so as to dispose the dished triangular portions thereof in the said triangular areas and said plane, marginal and diagonal portions in underlapping engagement with said posts and diagonal braces, said plane portions of said panels terminating at the edges of the members defining the triangular areas, applying end panels having outwardly dished substantially rectangular portions terminating short of one vertical end of said panels and connected with plane marginal portions thereof by outwardly inclined portions extending continuously between said plane and dished portions from the inside of the car, overlapping

the lower margins of said end panels upon said metallic members, swinging said end panels into underlapping engagement with said side plate flange and adjacent post so that the plane marginal portions engaging said post, side plate flange and metallic member terminate at the contiguous edges thereof, reinforcing the remaining plane marginal portions of said end panels, securing said panels to the members with which they are lapped and to the car ends and securing a wooden lining to said posts in spaced relationship to said outwardly dished portions of said panels.

9. A house car including: a metallic side sill; a metallic side plate having a depending flange; 15 metallic side posts; said posts being secured at their top and bottom ends to the outer face of said side plate flange and to the side sill respectively, said posts each having flanges extending lengthwise thereof; sheet metal side wall sheathing secured to the inner faces of said flanges of the posts, said metallic sheathing in the spaces defined by the posts, side plate and side sill being outwardly offset, said offset portions being united to those portions of the sheathing secured 25 to the inner faces of said post flanges by continuous outwardly inclined sections paralleling and disposed immediately adjacent said flanges of the posts and side plate, a wooden lining extending between said posts, means for fastening 30 said lining in position against said posts whereby perforation of the sheathing from nails driven from the inside of the lining is minimized.
